UNITED STATES PATENT OFFICE.

WILLIAM H. LANE AND LOUIS LANE, OF NEWARK, OHIO.

FIRE-PROOF LATH FOR SLATES.

SPECIFICATION forming part of Letters Patent No. 320,072, dated June 16, 1885.

Application filed February 24, 1885. (No model.)

To all whom it may concern:

Be it known that we, WILLIAM H. LANE and LOUIS LANE, both citizens of the United States, residing at Newark, in the county of Licking and State of Ohio, have jointly invented a new and useful Form of Fire-Proof Lath for Slates or Tiles, of which the following is a specification.

The object of our invention is to provide, in connection with a metallic lath, a suitable substance to which the slate can be firmly attached, and which will form a more or less elastic support for the same, thereby preventing breakage, together with provisions for securing closer contact between the slates and lath, thus affording a joint proof against snow, rain, &c.

To secure this our invention consists in a hollow or grooved metallic lath incasing and protecting on three sides a strip or filling of wood or other fibrous substance which it supports, and to which the slate is nailed or screwed in the usual manner. To protect this filling on the top, and to provide a packing between the lath and slate, we use a strip of asbestos or other fire-proof felt or paper in connection with a cement of a similar nature.

In the drawings, Figure 1 is a section.

A is the metal lath of such form as to support and incase the filling L. It is secured to the rafter K by means of the knee-bolt G and the nuts N N or other suitable device.

B is the strip of felt, with its edge at b in the small groove in L. When the filling is

put in, the two sides aa' are pressed together, 35 thus holding the filling and the edge b firmly. B is further secured at intervals with the brad D, and has its edge b' turned over and back, as shown.

The top of the filling strip L is of such form 40 that the slate F is in close contact with B, when the slate E rests upon the fold b' and clears the side a' of the lath A.

When the slate E is laid, the space I is filled 45 flush with the cement, which packs the joint as F is nailed or screwed down.

Fig. 2 is a general view with the parts marked the same as in Fig. 1.

We are aware of the use of asbestos and 50 other felts and cements for packing and fire-proofing, and of the use of iron and wood for slate-laths; but we are not aware of the form and combination, as above described and shown.

We claim and desire to secure by Letters 55 Patent—

The combination, with roofing slates or tiles, of hollow metallic lath incasing on three sides a filling of wood or other fibrous material whose exposed side is covered by a layer of felt 60 and cement, substantially as shown and described.

WILLIAM H. LANE.
LOUIS LANE.
